COMBINED ROTATABLE DIE AND MOBILE MOUNT

Frank E. Cole, Manchester, Mass., assignor to Essex
Plastic Machinery Company, Beverly, Mass., a corpora-
tion of Massachusetts

Filed Sept. 19, 1960, Ser. No. 62,201

Term of patent 14 years

(Cl. D54—8)

Fig. 1.

Fig. 2.

Fig. 3.

FIG. 1 is a front elevational view of a combined rotatable die and mobile mount showing my new design,

FIG. 2 is a perspective view thereof; and

FIG. 3 is a rear elevational view thereof.

The top is plain and the undisclosed side is substantially the same in appearance as the side shown.

I claim:

The ornamental design for a combined rotatable die and mobile mount as shown and described.
